(57) **CLAIM**

The ornamental design for a light fixture, as shown and
described.

DESCRIPTION

FIG. 1 is a bottom perspective view of a light fixture in
accordance with my design;

FIG. 2 is a plan view of the light fixture in accordance with my
design;

FIG. 3 is a front elevation view of the light fixture in accord-
ance with my design;

FIG. 4 is a back elevation view of the light fixture in accord-
ance with my design; and,

FIG. 5 is a side elevation view of the light fixture in accord-
ance with my design, the opposite side being a mirror image
of that shown.

The broken lines showing the environmental structure are for
illustrative purposes and form no part of the claimed design.
